UNITED STATES PATENT OFFICE.

WILLIAM D. INGLIS, OF RICHFORD, VERMONT.

WOOD STEAMER.

Application filed July 3, 1923. Serial No. 649,277.

To all whom it may concern:

Be it known that WILLIAM D. INGLIS, a citizen of the United States, residing at Richford, in the county of Franklin and 5 State of Vermont, has invented certain new and useful Improvements in Wood Steamers, of which the following is a specification.

This invention has reference to wood steamers for treating logs of wood preparatory to presenting the logs to knives to cut them into veneer strips, and its object is to so soften the wood as to prepare it for cutting into long strips of veneer when the steamed wood is mounted in an appropriate 15 lathe.

In accordance with the invention, the logs of wood are lowered into a vat with one end of the vat slightly higher than the other and the logs are conveyed first downwardly 20 into the vat of water and then upwardly therefrom, the wood being subjected to streams of steam which heat and saturate the wood as it is being treated.

In order that this operation may be accomplished, the logs are fed by chains downwardly through the vat of water through which the jets of steam are conducted and then upwardly from the vat at the upper end thereof. The length of the 25 vat is sufficient to subject the logs of wood to the heating action of the steam, thus permitting the logs to be appropriately softened. After the steaming action has continued for a sufficient length of time the 30 logs are then mounted in a suitable lathe and are presented to appropriate cutters for cutting the logs into strips to produce veneer.

The invention will be best understood 40 from a consideration of the following detailed description taken in connection with the accompanying drawings forming part of this specification.

In the drawings:

45 Figure 1 is a side elevation of a steaming vat constructed in accordance with the present invention.

Figure 2 is a section on the line 2—2 of Figure 1;

50 Figure 3 is a central longitudinal section through the steaming vat.

Figure 4 is a transverse sectional view of the vat on an enlarged scale and cut on the line 4—4 of Figure 1.

55 Referring to the drawings, it will be seen that the reference character 1 designates an elongated vat 1 which may be formed of concrete, the same being elongated with its opposite ends 2 and 3 rising above the normal water level in the vat. 60

The vat may be composed of a trough which has its open top closed by a cover or hood resting on the top of the side walls. The hood has its intermediate portion lying in spaced parallelism with the corresponding portion of the bottom of the trough and has its inclined end portions disposed in parallelism with the corresponding end portions of the trough. Associated with the bottom of the vat is a pair of endless chains 9 65 which are trained over the appropriate pulleys provided. It is to be observed that one stretch of the chain extends within the vat, while the other stretch is disposed on the exterior. Similar chains 7 are associated with the hood in a like manner. That is, the inner stretches of the chains are disposed within the vat with the other stretches disposed above the top of the vat. 70 These chains are likewise trained over the 75 pulleys provided for this purpose. At longitudinally spaced points, the inner stretches of the pairs of chains are connected together by relatively short and vertically disposed cross chains 10. The 80 logs 6 are bunched and confined between the chains 10 in the manner shown.

As more clearly seen in Figure 4, a pair of transversely disposed rails 15 are secured to the inner surface of the bottom of 85 the vat, and the bunches of logs are adapted to slide along these rails. Arranged between and on opposite sides of the rails are apertured steam conveying pipes 5. It is to be noted that the pipes are of the diameter to lie in a plane below the plane of 90 the upper faces of the rails 15.

The inner run of the chains 7 and 9 move along the interior of the vat, from the log receiving end to the log delivery end thereof. The logs are placed crosswise upon the inner runs of the chains 7 and 9 and the lower logs move upon the upper surfaces of the rail 15. The logs are assembled in groups, and the groups are separated from 100 each other by cross chains 10 which are connected with the inner runs of the chains 7 and 9. When the logs arrive at the delivery end of the vat, the cross chain sections are disconnected from the chains 7 and 9 which 105 permits the logs of the groups to roll out of the discharge end of the vat.

What is claimed is:

A plant for steaming logs comprising a vat having a horizontal intermediate portion, and inclined end portions which form the bottom of the vat, chains trained longitudinally around the bottom of the vat, rails extending the full length of the bottom of the vat and mounted thereon, perforated pipe sections disposed between the rails and lying below the plane in which the upper surfaces of the rails lie, a hood spaced from the vat, said hood having an intermediate portion which lies parallel with the inter-

mediate portion of the bottom of the vat, and inclined end portions which are disposed parallel with the corresponding end portions of the bottom of the vat, chains trained around the hood, cross chains connecting the chains around the hood with the chains around the vat, and closures for bridging the space between the ends of the hood and the corresponding ends of the vat. 15 20

In testimony whereof I affix my signature.

WILLIAM D. INGLIS.
